US00D783285S

(12) **United States Design Patent** (10) **Patent No.:** **US D783,285 S**
(45) **Date of Patent:** **** Apr. 11, 2017**

(54) **STORAGE COMPONENT**

(71) Applicant: **Herman Miller, Inc.**, Zeeland, MI (US)

(72) Inventors: **Sam Hecht**, London (GB); **Kimberlee Colin**, London (GB); **Philipp Von Lintel**, London (GB); **Ippei Matsumoto**, London (GB)

(73) Assignee: **Herman Miller, Inc.**, Zeeland, MI (US)

(**) Term: **15 Years**

(21) Appl. No.: **29/555,054**

(22) Filed: **Feb. 18, 2016**

Related U.S. Application Data

(62) Division of application No. 29/538,619, filed on Sep. 4, 2015, now Pat. No. Des. 752,865, which is a division of application No. 29/457,260, filed on Jun. 7, 2013, now abandoned.

(57) **CLAIM**

We claim the ornamental design for a storage component, as shown and described.

DESCRIPTION

FIG. 1 is a perspective view of a storage component.

FIG. 2 is a side view of the storage component.

FIG. 3 is an end view of the storage component.

FIG. 4 is a top view of the storage component; and,

FIG. 5 is a bottom view of the storage component.

The broken lines shown in the Figures are for environmental purposes only and do not form any part of the claimed design.
